UNITED STATES PATENT OFFICE.

GEORGE A. LAMBERT, OF UNION CITY, OHIO.

CAP FOR BOLTS OR SCREWS.

SPECIFICATION forming part of Letters Patent No. 531,465, dated December 25, 1894.

Application filed December 26, 1893. Serial No. 494,708. (No model.)

To all whom it may concern:

Be it known that I, GEORGE A. LAMBERT, a citizen of the United States, residing at Union City, in the county of Darke and State of Ohio, have invented certain new and useful Improvements in Portable Caps for Bolts or Screws; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to improvements in caps for bolts or screws, and the object of my invention is the provision of a simple and inexpensive cap which will afford a greater holding or securing surface than is provided by the ordinary head of the bolt.

The invention consists of a portable cap of novel and practical construction as will appear from the following description.

Figure 1 represents a sectional view of the cap and an elevation of the bolt, and Fig. 2 represents a perspective view with the bolt fitted in the cap.

My improved cap A, is provided with the opening B, having the tapering or countersunk walls C, to receive the conical head of

the bolt or screw C' and also has the tapered and curved securing or holding wings D, and the central portion is broadened to form the holding extensions D', as shown. The bolt C' has its head E of conical shape and provided with the curved feather F, for engaging the curved groove G of the cap to lock the head in the cap.

It will thus be seen that I provide a simple, cheap and practical cap which is of attractive appearance.

I claim—

1. A cap for bolts having the central opening provided with a curved groove, and a bolt having a curved feather adapted to form a locking engagement with the groove by turning the bolt.

2. A cap for bolts or screws having the holding portions and the countersunk opening having the curved groove and the bolt having the head provided with the spiral feather for engaging the groove when the bolt is turned to lock the bolt to the cap.

In testimony whereof I affix my signature in presence of two witnesses:

GEORGE A. LAMBERT.

Witnesses:
